UNITED STATES PATENT OFFICE.

EDWARD L. DELANY, OF BROOKLYN, NEW YORK, ASSIGNOR TO DELANY REALTY CORPORATION, OF BROOKLYN, NEW YORK.

FLUSH-TANK-OPERATING LEVER.

Application filed January 18, 1926. Serial No. 82,110.

My invention relates to improvements in flush tank operating levers.

The object of my invention is to provide a flush tank operating lever which can be readily attached to the tank and removed therefrom and in which a good strong and durable fulcrum is obtained for the operating handle and at the same time providing a link connection between the operating handle and the operating lever to insure of the proper movement of the lever.

Another object of my invention is to provide a flush tank operating lever of this character in which the operating handle may be readily removed and the flush valve lever readily removed, and at the same time providing means for attaching the same to the tank, and said attaching means serving as means for holding the fulcrum of the flush valve operating lever.

A further object of my invention is to provide a simple, cheap and effective flush tank operating lever which can be readily attached to any flush tank and at the same time providing certain details of structure and combination of parts hereinafter more fully set forth.

In the accompanying drawings:—

Figure 1 is a side elevation of my improved flush tank operating lever showing the tank in section.

Figure 2 is a longitudinal horizontal sectional view taken on the line 2—2 of Figure 1.

Figure 3 is a transverse vertical sectional view taken on the line 3—3 of Figure 1.

Figure 4 is a plan view partly in section showing a modified form of connection between the operating handle and the flush valve operating lever.

Figure 5 is a side elevation of a modified form of the invention.

Figure 6 is a top plan view partly in section of the modified form shown in Figure 5.

Referring now to the drawings, 1 represents the flush tank, which as is well understood by those skilled in the art, is provided with an opening 2 through which extends a tubular member 3, having on its outer end the annular flange 4 adapted to engage the outer wall of the tank 1, and limit the inward movement thereof. The tubular member 3 is externally threaded as

indicated at 5, and screwed thereon is a 55 nut 6 adapted to engage the inner face of the tank 1, and firmly lock the sleeve in the opening in the tank.

Screwed upon the inner end of the tubular member 3 is what I term a flush valve 60 lever bracket 7, which is provided with the downwardly extending arms 8 and 9 provided with openings 10 and 11 arranged in a horizontal plane and through which loosely passes the flush valve operating lever 12. 65 The lever 12 beyond the bracket 7 is turned or bent as indicated at 13, having the portion 14 extending parallel with the main portion of the lever, as clearly shown in Figure 2 of the drawings. Passing through the 70 sleeve 3 is the operating handle 15 carrying the porcelain or china knob 16, by means of which the handle is operated, as will be readily understood. The inner end of the handle 15 is enlarged as indicated at 17, 75 and passing through the flush valve lever bracket 7, the sleeve 3 and through an opening in the enlarged portion 17 of the handle 15, is a cotter pin 18 forming a fulcrum for the handle 15. This cotter pin 18 also 80 locks the flush valve lever bracket 7 on the sleeve. The extreme inner end of the handle 15 is bifurcated as indicated at 19 and into which extends the link 20 pivotally mounted therein by means of the cotter pin 85 21. The lower end of the link 20 is provided with an opening 22 through which extends the parallel portion 14 of the valve operating lever 12. By this structure it 90 will be seen that by pushing down the knob 16 the handle 15 is rocked upon the cotter pin 18 and the inner end of the handle moved upwardly. The link 20 draws the portion 14 of the flush valve lever 12 upwardly rocking the main portion thereof in the opening 10 and 11 in the flush valve lever bracket, and raising the end of the lever to 95 unseat the valve.

In the modification shown in Figure 4 the flush valve lever 12 terminates at the point 100 23 just beyond the arm 8 of the flush valve bracket, and said lever between the arms 8 and 9 is provided with a sleeve 24 through which the lever passes and said sleeve held rigidly thereto by means of the set screw 25. 105 The sleeve 24 is provided with the two outwardly extending arms 26 and 27 between which the link 20 passes, and is pivotally

connected therebetween by the cotter pin 28. In this form the operation is precisely the same as that described in the preferred form.

In the modification shown in Figures 5 and 6 the tubular member 3 is constructed exactly the same as that shown in Figures 1, 2 and 3. In this form, instead of having the flush valve lever bracket screwed on the tubular member the said flush valve lever bracket 29 slips loosely over the tubular member and is held against the inner face of the tank by means of the lock nut 30. This flush valve lever bracket extends upwardly and is provided with the inwardly extending arms 31 and 32 provided with oppositely arranged openings through which the flush valve operating lever 12 passes. The flush valve operating lever 12 is bent as indicated at 13 the same as that shown in Figure 2 of the drawings, and the portion 14 extending parallel therewith. The handle 15 is constructed and mounted in the tubular member the same as that shown in Figure 2 of the drawings, and like reference numerals indicate like parts. The difference in this form is the link 20 extends upwardly and has the portion 14 of the flush valve lever extending therethrough instead of downwardly, as shown in Figures 1 and 3 of the drawings. In this form the same connection as shown in Figure 4 could be employed for connecting the operating handle and the flush valve operating lever.

Having thus fully described my invention what I claim is:—

1. A flush valve operating mechanism comprising a tubular member adapted to be locked to the flush tank, a flush valve operating lever pivotally mounted on the tubular member, an operating handle extending through the tubular member and pivoted therein to have an up and down movement, and a loose connecting member between the inner end of the operating handle and the flush valve operating lever for raising and lowering the same.

2. A flush valve operating mechanism comprising a tubular member, means for securing the tubular member to the flush tank, a flush valve operating lever pivotally carried by the inner end of the tubular member, and removable therefrom, an operating handle passing through the tubular member, and pivoted therein to have an up and down movement, and a movable connecting member between the inner end of the operating handle and the flush valve operating lever for raising and lowering the same.

3. A flush valve operating mechanism comprising a tubular member, means for securing the same to the flush tank, a member removably supported by the tubular member, a flush valve operating lever pivotally mounted in said member, an operating handle passing through the tubular member and

pivoted therein to have an up and down movement, and a link connection between the inner end of the operating handle and the flush valve operating lever for raising and lowering the same.

4. A flush valve operating mechanism comprising a tubular member, means for securing the same to the flush tank, a sleeve mounted on the inner end of the tubular member, a flush valve lever pivotally carried by the sleeve, an operating handle passing through the tubular member, a horizontal pivot passing through the sleeve, the tubular member and the operating handle, whereby the handle has a vertical movement in the sleeve, and a loose connecting member between the inner end of the operating handle and the flush valve operating lever for raising and lowering the same.

5. A flush valve operating mechanism comprising a tubular member, means for securing the same to the flush tank, a flush valve operating lever pivotally carried by the inner end of the tubular member, an operating handle passing through the tubular member and pivotally mounted therein to have an up and down movement, an arm carried by the flush valve operating lever and extending around in a line with the inner end of the operating handle, and a link connecting said arm and the operating handle, whereby the lever is raised and lowered.

6. A flush valve operating mechanism comprising a tubular member, means for securing the same to the flush tank, a flush valve operating lever pivoted adjacent the tubular member, an operating handle extending through the tubular member and pivotally mounted therein, and a link connection between the inner end of the operating handle and the flush valve operating lever.

7. A flush valve operating mechanism comprising a tubular member, means for securing the same to the flush tank, a flush valve operating lever extending through the tubular member, means carried by the tubular member for pivotally supporting the flush valve operating lever, an operating handle passing through the tubular member and pivotally secured therein, and a link connection between the inner end of the operating handle and the flush valve operating lever.

8. A flush valve operating mechanism comprising a tubular member, means for securing the same to the flush tank, a member removably secured to the tubular member, a flush valve operating lever pivotally carried by said member, an operating handle passing through the tubular member and pivotally mounted therein, an arm carried by the flush valve operating lever and extending opposite the inner end of the operat-

ing handle, and a link connection between the arm and the inner end of the operating handle.

9. A flush valve operating mechanism comprising a tubular member, means for securing the same to the flush tank, a member removably carried by the tubular member, a flush valve operating lever pivotally mounted in said member, an operating handle extending through the tubular member, and pivotally mounted therein, an arm carried by the flush valve operating lever and extending opposite the inner end of the operating handle, and a link connection between the said arm and the inner end of the operating handle.

10. A flush valve operating mechanism comprising a tubular member, means for securing the same to the flush tank, a flush valve operating lever pivotally supported by the tubular member, an operating handle passing through the tubular member and pivotally mounted therein, the flush valve operating lever having its end bent around beyond the tubular member, and a link connection between the end of the bent portion of the valve operating lever and the operating handle.

11. A flush valve mechanism comprising a tubular member, means for securing the same to the flush tank, a flush valve operating lever pivotally supported by the tubular

member, and said lever having its ends bent around beyond the inner end of the tubular member, an operating handle passing through the tubular member and pivotally mounted therein, and a link loosely mounted on the bent end of the valve operating lever and pivotally connected to the inner end of the operating handle.

12. A flush valve operating mechanism comprising a tubular member, means for securing the same to the flush tank, an operating handle pivoted within the tubular member to have an up and down movement therein, a pivoted flush valve operating lever extending at right angles to the pivoted operating handle and a link connection between the inner end of the operating handle and the flush valve operating lever.

13. A flush valve operating mechanism comprising a tubular member, means for securing the same to the flush tank, an operating handle passing through the tubular member and pivoted therein to have an up and down movement, means carried by the tubular member for pivotally supporting the flush valve operating lever at right angles to the operating handle, and a link connection between the inner end of the operating handle and the flush valve operating lever.

In testimony whereof, I affix my signature.

EDWARD L. DELANY.
